TELEPHONE SYSTEM

David Langsford Clay, London, England, assignor to Siemens Brothers & Co. Limited, London, England, a British company

Application September 17, 1941, Serial No. 411,121
In Great Britain September 30, 1940

12 Claims. (Cl. 179—18)

The present invention relates to telephone systems and is especially applicable to private automatic and private automatic branch exchange systems. The chief object of the invention is to provide improved means for disposing of calls to privileged parties who may be absent from their instruments or who do not wish to be disturbed.

According to the present invention apparatus is associated with a privileged subscriber's line at the exchange and is adapted to be influenced by an operation on the part of the subscriber whereby calls directed by the exchange switching apparatus to the privileged subscriber's connection in the final selector multiple may be extended as desired to a circuit from which an answer or distinctive signal or other information can be given to the caller. For extending the call the apparatus conveniently includes a selecting switch adapted to be set in response to impulses transmitted by the privileged subscriber or by a marking applied by relays responsive to key operation by the privileged subscriber, the selecting switch having wipers connectable to contacts in the bank of the final selector appropriate to the privileged subscriber's number, outlets from the selecting switch being connected to the circuits to which a call may be extended. The apparatus may be so arranged that when the privileged subscriber's line is called, whether the call is to be extended or not, a tone or recorded message is given to the caller to indicate that he is calling a privileged line and completion of the call may be delayed pending further action by the caller or the arrangement may be such that only calls to be extended are so dealt with or again the privileged subscriber may decide at the time of setting the apparatus whether calls are to be directly connected or held in suspense.

The arrangements provide that while the apparatus is set for the extension of a call to another circuit the privileged party's line is available for use for outgoing calls.

The apparatus the subject of the invention can conveniently be connected to an existing system at the intermediate distributing frame or if such a frame is not provided, the existing wiring may be suitably cut and connected to terminals to which the apparatus may be connected thus avoiding disturbance of the multiple wiring. Access to the apparatus for the purpose of influencing it may be had by dialling a number appropriate to its connection in the banks of the final selector or a special connection may be provided over a controlling key and the impulsing or marking for the selective action may then be performed.

A specific embodiment of the invention will now be described by way of example with refer-

ence to the accompanying drawings comprising Figs. 1-3. In the drawings Fig. 1 shows diagrammatically the connections at a private automatic exchange (P. A. X) of an ordinary subscriber's line and the line of a privileged subscriber with which the automatic switching apparatus provided for the purpose of the invention is associated. Figs. 2 and 3 show the circuit arrangements of the automatic switching apparatus.

Referring first to Fig. 1, it will be seen that the lines of all subscriber's terminate on an intermediate distributing frame IDF where they are jumpered as required to the line circuits and the final selector multiple. The line of an ordinary subscriber designated OS is connected over the frame IDF to a line circuit OLC and over wire os to contacts in the final selector multiple designated by the number of the said ordinary subscriber. The line of a privileged subscriber designated PS is connected over the frame IDF to a line circuit PLC and also to the normal and first contacts of a selecting switch designated RR in the automatic switching apparatus. The contact in the final selector multiple designated by the number of the privileged subscriber is connected by wire ps over the IDF to the automatic switching apparatus designated by the reference MS from which it is extended by the switch RR in a manner determined by the setting of this switch. For the setting of the switch RR the automatic switching apparatus MS is connected over the IDF by a wire ms to a contact in the final selector multiple to which the final selector may be set for the purpose of exercising control of the apparatus which includes the switch RR. The outlets from the switch RR are connected to lines of ordinary subscribers over the IDF, one particular connection being shown from contacts 2 and 3 of the switch to line OS. The contacts of the switch are connected in pairs for a reason which will be clear from the description about to be given of Figs. 2 and 3. The last contacts of the switch are connected to a tone circuit. The connecting arrangements in the exchange are shown simply as consisting of a line finder LF and final selector FS, it being understood that one or more selecting switches can be included in the connection between the line finder and final selector and that arrangements for selecting and controlling a line finder would be provided in known manner.

If an intermediate distributing frame is not provided it will be necessary to allot two positions in the final selector multiple for the privileged subscriber's line, one such position being connected to the automatic switching apparatus the other being left disconnected. The line circuit corresponding to the former position will be disconnected as will also the line circuit corresponding to the position in the multiple con-

nected to the automatic switching apparatus for its setting.

Reference will now be had to Figs. 2 and 3 of the drawings. On the left of Fig. 2 are shown diagrammatically the speaking and test wire wipers and their contact banks of final selectors, FS. The outlets from the banks of the final selectors are multiplied in the usual manner and in the upper of the two selectors shown the outlet for the control of the automatic switching apparatus MS is shown while in the lower of the two selectors the outlet shown is that corresponding to a privileged subscriber's line. The apparatus MS comprises an 11-contact single motion reverse drive stepping switch RR having 7 wipers and contact banks and driven by magnet RM. The first 10 outlets from the switch in the banks of wipers RR5, RR6 and RR7 are connected in pairs, contacts 0 and 1 being connected to the privileged subscriber's own line, contacts 2 and 3 and so on to contacts 8 and 9 being connected to the lines of other subscribers to which an incoming call can be extended by the apparatus. The last contacts, i. e., contacts 10, are connected to a tone circuit. The off-normal contacts in the bank of wiper RR1 are commoned; similarly, the off-normal contacts in the bank of wiper RR2 are commoned. The setting of the switch RR is controlled by relays A, B and C and relays P and Q determine the contact of a pair over which a call is to be extended. These relays are operated on alternate impulses and by their condition at the end of an impulse train determine whether the call shall be extended directly or only after some further action has been performed by the caller, and in the latter case a tone is reverted to the caller to inform him that further action is required. In this way it is possible for the caller to abandon the call if the matter is not sufficiently urgent to warrant disturbing the privileged subscriber. The switching through of the connection is carried out by the relays shown in the lower part of the figures, H being a test relay and TR a ring tripping relay. Relay AA responds to a further impulse train which may comprise any number of impulses dialled in response to a tone reverted over wire RT. BB and CC are slow releasing release and dialling relays respectively and E is a slow releasing relay which measures off a fleeting test period. ON is a relay the function of which corresponds to the more usual off-normal contacts of the selecting switch RR.

In the normal position of the switch RR calls to the privileged subscriber are extended by the final selector over unoperated contacts q_2 , q_3 and q_4 of relay Q and wipers RR5, RR6 and RR7 in their normal or 0 contact position to the privileged subscriber's line, the called line being marked busy by earth applied in the final selector over the test wiper thereof and wiper RR1.

If the privileged subscriber does not wish to be disturbed except on an urgent matter, or if he leaves his instrument and goes to the position of another subscriber to whose line an incoming call can be extended by the apparatus MS or if he leaves his instrument and goes to a position to which the apparatus MS cannot extend a call, for example from the exchange system, he sets the apparatus MS accordingly. To do this he dials the number allocated to the apparatus and then by means of a further impulse train he sets it to the desired position. This can be done from any telephone on the P. A. X. system.

In response to the dialling of the number allocated to the apparatus MS, relay N is operated by earth applied by the final selector test relay to the test wiper of the final selector and the test bank contact corresponding to the privileged subscriber's line is earthed over contact n_1 to guard the line at this time. If the switch RR is in the normal position, relay A in the apparatus MS operates over a preceding loop and at contact a_2 closes a circuit over wiper RR2 on contact 0 for release relay B. Relay B operates and at contact b_1 opens the homing circuit for switch RR, at contact b_2 prepares a holding circuit for itself, at contact b_3 prepares a circuit for relay C and at contact b_4 connects dialling tone over wire DT, contact 0 and wiper RR4 to a third winding of relay A. This tone is transmitted to the caller by induction in the line windings of relay A.

When the first impulse of the setting train is dialled, relay A falls back during the "break" period of the impulse and at contact a_1 operates relay C. On the subsequent reoperation of relay A a circuit is closed over contacts a_1 and c_1 for magnet RM which becomes energised. At the same time a circuit is closed over contacts a_2 and c_2 for the right-hand winding of relay P. Relay P operates and at contact p_1 prepares an energising circuit for its left-hand winding and at contact p_2 prepares a holding circuit for itself and an operating circuit for relay Q. If further impulses follow, relays B and C hold during such impulsion. At the second release of relay A magnet RM is de-energised and steps the wipers to contacts 1. Wiper RR2 is now included in the holding circuit for relay B, contacts 1 to 10 in the bank associated with wiper RR2 being commoned. A short circuit is removed from winding (I) of relay Q at contact a_2 and this relay operates by means of its winding (I) in series with the right-hand winding of relay P and wiper RR3. Contact q_1 disconnects the right-hand winding of relay P from the circuit over contact a_2 and connects the left hand winding of that relay in its place. When relay A re-operates the left hand winding of relay P is energised and as this winding is arranged to oppose the right-hand winding, the relay is released. Winding (II) of relay Q is energised in parallel with relay P and relay Q remains held. Thus after each odd impulse, relay P remains operated and after each even impulse relay Q remains operated until the next impulse break occurs or relay C releases consequent on the continued energisation of relay A.

When the switch has been set to the desired position by the transmission of the appropriate impulse train, the privileged subscriber replaces his receiver and takes no further action until he desires to alter the setting; consequently relay A releases followed by relays B and C. If an even number of impulses has been transmitted for the setting of the switch the opening of contact c_2 following the continued operation of relay A after the transmission of the last impulse releases relay Q and similarly if an odd number of impulses have been transmitted the removal of the short-circuit about winding (I) of relay Q is similarly performed. Relay N releases and removes the engaged marking from the privileged subscriber's line. A call for the privileged subscriber is now extended over one of the contacts 0 to 9 or the connection is routed to a tone circuit over contacts 10 of the switch RR.

To change the setting of switch RR from one

off-normal position to another position the privileged subscriber dials the number allocated to the apparatus and relay A operates. Relays B and C being unoperated and the switch being away from its normal contacts, a circuit is closed over contacts *a*, *c1*, contacts *rm* operated by magnet RM, wiper RR1 and contact *b1* for magnet RM and the magnet operates by self-interruption to home the switch. In the home position relay B operates and connects up dialling tone and the subscriber can then proceed with the setting of the switch if such a further setting is desired.

If the switch has been set to one of the even contacts 2, 4, 6, 8, 10, an incoming call is extended directly to the line of the subscriber connected to the particular contacts or to the tone circuit while if the switch has been set to one of the odd contacts 1, 3, 5, 7, 9 a tone is reverted to the caller. The operations in the latter case are as follows. Relay Q has remained operated after the setting of the switch and battery potential for the final test relay is applied over contact *q4* and relay AA is connected to the speaking wires over contacts *q2* and *q3*. When the apparatus is seized, relay AA operates over a preceding loop and at contact *aa1* operates relay BB. Contact *bb1* connects tone over wire RT and contact *on1* to a third winding on relay AA and the tone is transmitted to the caller by induction in the other windings of relay AA. On hearing the tone the caller dials another impulse train which may comprise a single impulse or any number of impulses. When relay AA releases a circuit is closed over contacts *aa2*, *bb3* and *on3* for relay CC and this relay operates. Contact *cc1* prepares a circuit for relay E, contact *cc2* closes a holding circuit for relay CC and contact *cc3* disconnects the testing circuit of relay H. When relay AA re-operates, contact *aa2* completes the prepared circuit for relay E and this latter relay operates. Contact *e1* operates relay ON which holds over contacts *on2* and *bb2*, contact *e2* connects relay H to the test wiper RR7, contact *e3* disconnects the busy and ringing signal circuits and contact *e4* disconnects winding (I) of relay TR. Contact *on1* disconnects tone wire RT and prepares for the transmission of ringing or busy signal and contact *on3* opens the operating circuit for relay CC. Any further impulses in the train produce no effective circuit changes. When relay AA remains steadily operated after the last impulse of the additional train has been transmitted, relay CC releases and at contact *cc3* closes the testing circuit for relay H. If the line is free, relay H operates over its right-hand winding and locks up over its left-hand winding and contacts *h1* and *bb2*. Contacts *h2* and *h3* connect the line wires to wipers RR5 and RR6, contact *h4* earths the test wiper RR1 to mark the line engaged and contact *h5* connects up wire RS over which ringing signal is transmitted. Shortly after the operation of relay H, relay E releases consequent on the opening of contact *cc1* and contact *e2* disconnects the right-hand winding of relay H, contact *e3* connects wire RS over contacts *tr4*, *h5*, *on1* and *bb1* to the third winding on relay AA and contact *e4* connects relay TR in the ringing circuit. The bell of the subscriber connected up over the wipers of switch RR is rung in the usual manner and the caller receives a ringing signal over wire RS. When the called party replies, relay TR operates, closes a locking circuit for itself over its winding (II) and contacts *tr1* and *bb2*, switches the line through at contacts *tr2* and *tr3* and disconnects the ringing signal at

contact *tr4*. The circuit is now in the conversational condition.

When the caller clears at the end of the conversation, relay AA releases followed by relay BB. Contact *bb2* opening, relays ON, TR and H release and the circuit resumes its normal condition.

If at the time of release of relay CC the called line is busy, relay H will not operate and on the subsequent release of relay E busy signal over wire BS is transmitted to the caller.

If the switch has been set to contacts 10, relay H operates as for a free line and a circuit for relay TR is completed immediately relay E releases and a number unobtainable or other distinctive tone is reverted from a circuit connected to contacts 10.

If it be desired that all calls to be extended over contacts other than the normal are to be held in suspense, relays P and Q can be dispensed with and an off-normal relay may be connected between a back contact of contact *a2* and wiper RR3, the normal contact in the bank of this wiper being unconnected and the off normal contacts connected to battery. Contacts of this relay would be substituted for contacts 2, 3 and 4 of relay Q and only one position per circuit to which calls may be extended would be required in the banks of wipers RR5, RR6 and RR7. Obviously by omitting relays P and Q or the off-normal relay referred to and connecting the contacts allocated to the privileged subscriber in the bank of the final selector directly to relay AA and contacts *tr2* and *tr3* and connecting the test wire contact over the back of contact *n1* directly to battery all calls can be arranged to be held in suspense.

If the privileged subscriber is conveniently situated with respect to the exchange and if it is not desired to effect a setting of the apparatus MS from any position other than the privileged subscriber's position, setting may be effected by a marking applied to the switch by relays operated by means of a set of keys at the privileged subscriber's location. Such means are well known in the art and consequently a particular description of such means has not been thought necessary.

Although the switch RR has been described and illustrated herein as an 11-point single motion switch, a larger switch or a two motion switch may be employed, the means for setting such a switch taking any well-known form.

It will be appreciated that the arrangements shown can be added to an exchange without disturbing the existing circuits, all that is necessary being to connect the apparatus as required to terminals on the intermediate distributing frame and to cross-connect the terminals on the frame in a suitable manner as indicated herein. If there should be no intermediate distributing frame, the wiring concerned may be cut and connected to terminals to which the required connection to the additional apparatus can readily be made.

It will be clear from the preceding description that while the switch RR is in an off-normal position the privileged subscriber is quite free to make outgoing calls in the ordinary manner.

What I claim as new and desire to secure by Letters Patent is:

1. In a telephone or like system, a calling subscriber's line, a called subscriber's line, switching equipment normally responsive to certain predetermined operations performed by the calling subscriber to seize said called line, if same

is free, preparatory to the completion of a call thereto, means for at times preventing said equipment from seizing said called line even though same is free, means for signalling the calling subscriber at such times, and means thereafter operated responsive to an additional operation performed by the calling subscriber for seizing said called line.

2. In a telephone or like system, a calling subscriber's line, an idle called subscriber's line, switching equipment normally responsive to certain predetermined operations performed by the calling subscriber to seize said idle called line, and means operated at times for causing said equipment to seize said idle called line responsive only to an additional operation performed by said calling subscriber after said predetermined operations have been performed.

3. In a telephone or like system, a calling subscriber's line, an idle called subscriber's line, switching equipment normally responsive to certain predetermined operations performed by the calling subscriber to seize said idle called line, and means at times pre-set over one of said lines prior to performance of said predetermined operations for causing said equipment to seize said idle called line responsive only to an additional operation performed by said calling subscriber after said predetermined operations have been performed.

4. In a telephone or like system, an automatic switch having a contact bank, a plurality of lines each normally appearing in but a single position in the bank of said switch, and means operated variably to cause any desired one of said lines to appear in a plurality of positions in the bank of said switch, whereby a subsequent operation of said switch to any of said plurality of positions will select said one line.

5. In a system as claimed in claim 4, means in said switch for seizing said one line substantially without delay if it is selected by operation of said switch to a particular one of said plurality of positions at a time when said one line is idle, and means for delaying the seizure of said line if it is selected by operation of said switch to a different one of said plurality of positions at a time when said one line is idle.

6. In a telephone or like system, an automatic switch having wipers and a bank of contacts accessible to said wipers, means for moving said wipers to engage any set of contacts in said bank, at least three lines each normally connected to but a single set of contacts in said bank, and means operated selectively to cause any desired one of said lines to be connected to at least one additional set of contacts in said bank, whereby said one line thereafter may be selected by operation of said wipers to any of a plurality of different sets of contacts in the bank of said switch.

7. In a telephone or like system, an automatic switch having wipers occupying a normal position and a bank of contacts accessible to said wipers, a plurality of lines each permanently connected to a different set of contacts in said bank, a special set of contacts in said bank, means for moving said wipers off normal to select any set of contacts in said bank, selector means operated variably over said wipers when same occupy a particular off-normal position to connect any desired one of said lines to said special contact set, means for then restoring said switch to nor-

mal without disconnecting said one line from said special contact set, whereby said one line thereafter may be selected by the movement of said wipers, under control of said first means, either to said special contact set or to the contact set to which said one line is permanently connected.

8. In a telephone or like system, a first switch, a second switch accessible to said first switch, a plurality of subscribers' lines each connected in multiple to the contact banks of both said switches, means for operating either of said switches to connect directly with any desired one of said lines over the contact bank of that switch, said means effective at times to cause said first switch to connect with said second switch while said second switch remains connected to some one of said lines to which it was previously operated, thereby to connect with said last-mentioned line over said two switches in series.

9. In a telephone or like system, a first switch, a second switch accessible to said first switch, a plurality of subscribers' lines each connected in multiple to the contact banks of both said switches, and means for extending a call to any desired one of said lines either by seizing said first switch and operating it to select said desired line in its own contact bank or by operating said second switch to select said desired line and then seizing said first switch and operating it to select said second switch.

10. In a system as claimed in claim 9, means in said second switch operated responsive to a seizure of that switch by said first switch for signalling the calling subscriber, and means in said second switch thereafter controlled by an operation performed by said calling subscriber in response to said signal for seizing said desired line.

11. In a telephone or like system, a first switch, a second switch accessible to said first switch, a plurality of subscribers' lines each connected in multiple to the contact banks of both said switches, means for seizing said first switch, operating it to seize said second switch, and then operating said second switch over said first switch to connect with any desired one of said lines, means for thereafter releasing said first switch without releasing said second switch, and means for subsequently seizing said one line either by operating said first switch to connect directly with said one line over its own contact bank or by operating said first switch to connect with said second switch.

12. In a telephone or like system, a plurality of first switches, a second switch accessible to all of said first switches, a plurality of subscribers' lines each connected in multiple to the contact banks of all of said switches, means for operating any one of said first switches to connect over its contact bank with any one of said lines or with said second switch and, if said second switch is connected with, for controlling said second switch over said one first switch to connect with any desired one of said lines, and means for operating any other one of said first switches to connect with said second switch while said second switch remains connected to said last-mentioned line, thereby to extend a connection over said other first switch and said second switch to said last-mentioned line.

DAVID LANGSFORD CLAY.
